UNITED STATES PATENT OFFICE

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY

RACK

Application filed April 15, 1924. Serial No. 706,777.

My invention relates to the temporary support of various objects, as cemented portions of shoes which it is desired to dry partially before further operating upon them.

In the making of rubber-soled shoes, it is customary to deliver the tops cemented by one operator to an inspector, who turns and sorts them in preparation for the next manufacturing step. Until the applied coating has become somewhat hardened, however, they are not handled, but are preferably kept separated from one another, to avoid smearing. An object of this invention is to provide means whereby work-pieces of this character may not only be held temporarily in the proper relation for drying, but may also be transferred conveniently from one operator to another. In the accomplishment of this object, there is furnished by my invention a novel rack organization comprising a support rotatable upon a base, on which support are a plurality of carriers mounted to turn about an axis lying at an angle to the axis of rotation of the support, each carrier being free to be positioned about its axis and each having work-receiving projections. The turning of the carriers upon the support so presents any one of the projections to an operator that the work-pieces may be placed upon or removed from them with minimum effort, while the rotation of the support allows the work of one operator to be readily made accessible to another. Means is preferably furnished or retaining the support and carriers in such predetermined positions as the operators may choose. As herein illustrated, the support consists of a standard, upon which a head is rotatable, this head having, turning upon it, opposite wheels, from which project pins adapted to each receive a series of work-pieces slightly separated from one another. Latch devices, appearing as co-operating projections and depressions, may be employed to determine the position of the support and carriers.

A particular embodiment of the invention is shown in the accompanying drawing, in which

Fig. 1 is a side elevation of my rack;

Fig. 2, a front elevation of the upper por-

tion thereof, with parts broken away, as viewed from the left in Fig. 1; and

Fig. 3, an enlarged sectional detail on the line 3—3 of Fig. 1.

Rising from a flange or foot 10, adapted to be bolted to a bench, is a substantially vertical standard 12, which may be furnished by a section of tubular rod or pipe threaded into the flange. The foot and standard together furnish a base for the active elements of the device. Surrounding the standard is a collar 14, secured in place by a set-screw 16. About the end of the standard and resting upon the collar is a head, conveniently furnished by a sleeve 18. This sleeve may have at 20 a bearing upon the exterior of the standard for a limited distance vertically, the upper portion of the sleeve being held in correct axial alignment with its support by screws 22, here shown as four in number, threaded through the sides of the sleeve and contacting at their inner ends with the standard. At the upper extremity of the sleeve is a transverse opening 24, extending horizontally and receiving a spindle 26 fixed in position by a set-screw 28. The spindle is shown as extending for equal distances upon opposite sides of the sleeve, and has, turning about it, at each side, a carrier, shown as in the form of a wheel 30, the hub, radiating spokes and peripheral rim of which may well be of cast metal. The carrier-wheels are maintained against displacement upon the spindle by collars 32 secured outside the wheels by set-screws 34. Just within the periphery of each wheel is a series of bosses 36, preferably horizontal and perforated to receive pins 38 secured by set-screws 40 threaded into the bosses. Five of these pins are shown upon each wheel, lying horizontally and spaced equally about the circumference of the wheel. They project outwardly, or away from the associated wheel, and are of such length that each may support the desired number of shoe-tops or other work-pieces without so crowding them that coated portions are brought into contact with those upon adjacent pieces which are uncoated. The angular separation of the pins is sufficient to maintain the series of supported pieces from striking those upon the succeeding pins as the wheels are turned.

The pins 38 are preferably tubular, and each has movable within it a rod 42 serving as a latch member. About an outer reduced portion 44 of each rod is a helical spring 46 resting at one extremity against the body of the rod and at the other against a sleeve 48 fixed in the end of the pin-opening, and through each sleeve the corresponding rod slides. A head 50 is fixed upon the portion 44 outside the sleeve, and allows the latch member to be drawn outwardly against the force of the spring. The inner extremity of each latch-rod is tapered at 51 to enter, under the influence of the spring, a depression 52 in a retaining arm 53 mounted to turn about the spindle 26. Each arm, there being one for each of the wheels 30, may be secured in different angular positions by a segment 54 projecting from one side of the arm and having a slot, through which passes one of the screws 22. A nut 55 upon the outer end of this screw bears against the segment to clamp the arm in its adjusted position. With a latch-rod of either of the wheels 30 drawn out of the depression 52 which it may have been engaging, such wheel may be rotated until the next rod approaches the arm, at which time the end of the rod rides over a cam-incline 56 and enters the depression 52. These inclines 56 are situated upon both sides of the depression, so the rod may be raised to enter the depression for movement from either side. This rotation of the wheel presents the pins in new work-receiving positions, the exact relation of these pins being varied to suit the needs of an operator by change in the angular position of the arm 53. This simultaneously effects the adjustment of all the pins as they are secured by their respective latch-rods 42.

In using my improved rack, the flange 10 may be attached to a bench in a position between two operators, as one who cements shoe-tops and one who inspects them. Normally, the sleeve 18 is so retained in its angular position about the standard 12 that the two series of pins 38 project longitudinally of the bench substantially at right angles to the axis of the sleeve, each series being adjacent to an operator's position. It is here retained by a latch device, which may consist of a projection 58 upon the upper side of the collar 14 arranged to enter either one of two diametrically opposite depressions 60 in the bottom face of the sleeve. This engagement is maintained by the weight of the support and the parts which it carries, an upward movement of these, in turn, allowing the depression which is in co-operation with the projection to be disengaged therefrom, and the movement to continue until the opposite depression rides over the projection, at which time the relation of the pins 38 to the operators' positions will have been reversed. As the cementing operator coats the tops, she

places them one by one upon a pin 38 which is conveniently situated and retained against revolution by engagement of one of the rods 42 with the depression 52, the depression being located to give the pin in use the preferred angular position by adjustment of the arm 53. This is continued until the full capacity of the pin has been reached. Then the wheel may be rotated until another of the rods engages the depression 52, the latching means chosen being one which will bring a succeeding pin at a convenient height for the operator to place upon it the coated work. The utilization of the pins may thus progress until all are full, whereupon the sleeve 18 is turned. This may be effected, if desired, by a bar 62 inserted in the spindle 24, which is shown as tubular. It will be understood that, while the cementer has been using one side of the rack to receive the work-pieces, the inspector will be occupied with those which have previously been placed upon the other side, the last-mentioned operator being supplied with fresh work whenever the rack is rotated about its vertical axis. In the same manner as the cementing operator, the inspector may turn the carrier-wheel which is presented at her position so that one of its pins will be suitably located for her to easily remove the work-pieces therefrom.

Having described my invention, what I claim as new and desire to secure by Letters Patent of the United States is:

1. A rack comprising a base, a support free to be rotatably positioned thereon, and a plurality of carriers mounted to turn about an axis lying at an angle to the axis of rotation of the support, each carrier being free to be positioned about its axis independently of the associated carriers and each having projections extending outwardly from the support and each arranged to hold separately a series of work-pieces.
2. A rack comprising a rotatable support, a plurality of carriers rotatable upon the support and each having a series of spaced work-receiving projections, and means for retaining each of the carriers in a plurality of predetermined rotative positions corresponding to the projections.
3. A rack comprising a rotatable support, a plurality of carriers rotatable upon the support and each having work-receiving projections, plural means for retaining each of the carriers in a plurality of predetermined rotative positions, and means arranged to vary simultaneously the angles at which the carriers are retained by all the plural means.
4. A rack comprising a rotatable support, two rotatable carriers spaced from each other upon the support and provided respectively with oppositely projecting work-receiving elements, a latch device arranged to retain the support in different rotative positions, and a latch device for each of the carriers.

5. A rack comprising a standard, a head mounted to turn upon the standard, a plurality of wheels rotatable upon the head and each having a plurality of work-receiving pins, and means for fixing the head against movement with the wheels at either of two opposite operating positions.

6. A rack comprising a standard, a head mounted to turn upon the standard, and a plurality of wheels rotatable upon the head and each having a plurality of work-receiving pins, the head and wheels each being provided with co-operating projections and depressions arranged to retain them in predetermined positions in their rotation.

7. A rack comprising a standard, a sleeve rotatable upon the standard, a horizontal spindle projecting oppositely from the sleeve and fixed against movement thereon, wheels rotatable upon the opposite portions of the spindle, and horizontal pins projecting oppositely from the wheels adjacent to their peripheries.

8. A rack comprising a standard, a sleeve rotatable upon the standard, a horizontal spindle projecting oppositely from the sleeve, wheels rotatable upon the opposite portions of the spindle and provided with spring-latches, horizontal pins projecting oppositely from the wheels adjacent to their peripheries, and a member secured to the sleeve for engagement by the latches.

9. A rack comprising a standard, a sleeve rotatable upon the standard, a horizontal spindle projecting oppositely from the sleeve, wheels rotatable upon the opposite portions of the spindle and provided with spring-latches, horizontal pins projecting oppositely from the wheels adjacent to their peripheries, a member secured to the sleeve for engagement by the latches, and means arranged to vary the position of the member.

10. A rack comprising a vertical rod, a collar fixed upon the rod, a sleeve rotatable about the rod, the collar and sleeve being provided with a projection and opposite depressions co-operating with the projection, a horizontal spindle mounted upon the sleeve, a wheel rotatable about the spindle at each side of the sleeve and having peripheral depressions, pins projecting horizontally from the outer sides of the wheels, and spring-latches carried by the pins.

11. A rack comprising a standard, a head rotatable thereon, a spindle fixed in the head, said spindle being tubular and arranged to receive a bar by which the head may be turned, and work-carrying wheels rotatable upon the spindle at opposite sides of the head.

12. A rack organized for use between adjacent operating positions and comprising a vertical standard, a sleeve free to be rotatably positioned on the standard, a horizontal spindle projecting oppositely from the sleeve, a wheel free to be rotatably positioned upon

each extremity of the spindle, projections extending from each wheel and arranged to receive simultaneously work-pieces applied by the operators at both positions, means arranged to retain the sleeve with its respective wheels at either of the operating positions, and means arranged to retain each wheel in a series of angular positions about its axis and thus present the projections successively in a definite relation to the operator at the position in which said wheel is located.

In testimony whereof I have signed my name to this specification.

JOHN W. COSGROVE.
